(57) CLAIM

The ornamental design for poster bed, as shown and described.

DESCRIPTION

FIG. 1 is a perspective view of a poster bed, showing my new design;

FIG. 2 is a front view of the footboard portion of the bed; FIG. 3 is a front view of the headboard portion of the bed; FIG. 4 is a side elevational view, the opposite side being a mirror image thereof; and,

FIG. 5 is a top plan view thereof.

The headboard and footboard are shown separately for convenience of illustration.
